UNITED STATES PATENT OFFICE.

FRANK E. BACHMAN, OF BUFFALO, NEW YORK.

FILTER.

SPECIFICATION forming part of Letters Patent No. 739,474, dated September 22, 1903.

Application filed December 14, 1901. Serial No. 85,878. (No model.)

To all whom it may concern:

Be it known that I, FRANK E. BACHMAN, a citizen of the United States, residing at Buffalo, in the county of Erie and State of New York, have invented certain new and useful Improvements in Filters, of which the following is a specification.

This invention relates to an improved combined filter and precipitating tank in which the precipitating-compartment is arranged above the filtering-compartment; and the object of the invention is to simplify and cheapen apparatuses of this character by combining the precipitating and filtering devices in one and the same vessel or tank.

The invention also relates to certain details of construction, all of which will be fully and clearly hereinafter described and claimed, reference being had to the accompanying drawings, in which—

Figure 1 is a top plan view of a pair of the improved filters connected together by suitable piping. Fig. 2 is a side elevation of the same. Fig. 3 is a section on line *a a*, Fig. 1. Fig. 4 is a detached bottom view of the vertical connecting-tube. Fig. 5 is a detached view of one of the strainer-plates. Fig. 6 is a fragmentary section on line *b b*, Fig. 3. Fig. 7 is a detached vertical section through a three-way valve.

In referring to the drawings in detail like characters designate like parts.

In the preferred construction of the invention shown in the drawings two upright and closed vessels or tanks are coupled together, and as these tanks are slightly different in construction one will be designated by the letter A and the other by the letter B.

The vessel or tank A is divided into two compartments 1 and 2 by a partition or diaphragm 3, which is concaved or dished, as shown in Fig. 3. The lower and larger compartment 1 has a horizontal plate 4, arranged slightly above the bottom of the vessel or tank, which is provided with slots 5, and a series of strainer-plates 6, provided with narrow slits 7, are secured to the plate 4 above the slots 5. The compartment 1 is filled or nearly filled with granular filtering material 8, which is supported upon the plate 4. The upper compartment 2, which is the mixing and precipitating compartment, has a top opening 9, and

a vertical tube 10 extends down from said opening to within a short distance of the bottom of the compartment. A deflecting-plate 11 is secured to the lower exterior of the tube 10 and slightly above the diaphragm 3 by a series of vertical connections 4^a. (See Fig. 3.) A blow-out pipe 12 has its inner extreme extending between the diaphragm 3 and the deflecting-plate 11 and serves to remove the heavier particles of impurities which collect in the dished diaphragm.

The vessel A is connected to the vessel B by a tubular connection or pipe 13. The vessel or tank B is similar to the vessel or tank A with the exception that the central tube 10 is dispensed with and in lieu thereof a plate 14, of curved cross-section, is riveted to the inner surface of the vessel or tank to form a vertical water-conducting passage 15. This plate extends to the top of the tank or vessel, and a horizontal deflecting-plate 16 is suspended beneath its lower extreme by vertical connections 17 and serves to deflect the water as it leaves the passage 15. The pipe 13 extends into communication with the passage 15, so that the precipitating-compartment in tank B communicates directly with the precipitating-compartment in tank A. A pipe 18 for supplying the first precipitating chemical to the water connects with the water-supply-pipe connection 19 at the top of the tank A, and a second pipe 20 for supplying the second precipitating chemical connects to the pipe 13, so that the precipitating chemical is introduced into the water before it enters the precipitating-compartment in either tank. The blow-out pipe 12, extending from each precipitating-compartment, unite at a common discharge-pipe 21.

The two vessels or tanks are connected by a system of piping, so that their respective filter-beds can be washed out independently. An upper horizontal pipe 22 connects at each end to the upper extreme of a vertical pipe 23, and the lower ends of the vertical pipes are secured to three-way valve connections 24, formed substantially as shown in Fig. 7. An intermediate horizontal pipe 25 connects the two three-way valves 24, and horizontal pipes 26, extending from the filtering-compartments, are coupled to the lower connections of the three-way valves. The upper

horizontal pipe 22 is also connected to the precipitating-compartment of tank B by a horizontal outwardly-extending pipe 27. A vertical waste-pipe 28 extends from the horizontal pipe 25. A lower horizontal pipe 29 has a vertical connecting-pipe 30 extending therefrom, which is to be coupled to piping for conveying the filtered water to any desired point. Vertical pipes 31 connect at their upper extremes to the ends of the horizontal pipe 29 and at their lower ends to radial horizontal pipes 32, which extend into communication with the vessels or tanks A and B below the plate 4. A horizontal pipe 33 extends from each of the horizontal pipes 32 and has a shut-off valve 34. Two of these pipes 33 are employed, and each is connected to the horizontal pipe 29 by vertical pipes 35. Each of the vertical pipes 35 has a shut-off valve 36. The vessels or tanks are provided with several test-tubes 37, 38, and 39, which connect with the various points, and have faucets 40, 41, and 42, through which the water may be drawn at different stages in the precipitation purification to ascertain the quality of the work. The vessels or tanks can be provided with manholes and openings 43 at various points for convenient access to the interior for repair or replacement.

The operation is as follows: The water passes into the precipitating-compartment in tank A through the tube 10, being supplied with precipitating chemicals before it enters the compartment by the pipe 18, as before described. From the precipitating-compartment in tank A it passes through the connecting-pipe 13 into the precipitating-compartment in tank B, being supplied with the second precipitating chemical as it passes through the pipe 13, as before described. From the precipitating-compartment in tank B it passes out through the pipe 27 into and through the horizontal and vertical pipes 22 and 23 and into and through the horizontal pipes 26 into the two filtering-compartments, where it is filtered. The filtered water is drawn from the filtering-compartments through the pipes 29, 31, and 32, and is conducted to the desired point by piping connected to the vertical pipe 30. In operating the filters the disks 44 of the three-way valves are closed against the seat 45 to permit the water to pass into the filtering-compartment and prevent the water flowing into the waste. When it is desired to clean out one of the filtering-compartments, the disk 44 of the three-way valve of that filtering-compartment is moved to bring it against the seat 46, or substantially in the position shown in Fig. 7, thereby shutting off the passage of water from the precipitating-compartments into that filtering-compartment and opening a passage from the filter-top into the waste-pipe. The heavier impurities collected in the dished diaphragm 3 are removed through the blow-out pipes 12 when the shut-off valves 47 are opened. The principal advantages of this improve-

ment are that by coupling two tanks of this character together two precipitating-compartments and two filtering-compartments are obtained, and at the same time but two tanks or vessels are required, thereby greatly simplifying and cheapening the apparatus.

I claim as my invention—

1. A plurality of combined precipitating and filtering tanks coupled together and each divided into two compartments by a solid diaphragm, one of said compartments containing filtering material and the other constituting a precipitating-compartment, and means whereby the liquid to be purified passes through the precipitating-compartments of the tanks and then through the filtering-compartments, substantially as set forth.

2. A combined precipitating and filtering tank divided into two compartments by a solid dished or concaved diaphragm, one of said compartments containing filtering material and the other constituting a precipitating-compartment and the dished diaphragm forming a collecting-pocket for the impurities in the precipitating-chamber.

3. A combined precipitating and filtering tank having a top opening, a solid imperforate dished diaphragm dividing said tank into upper and lower compartments, one of said compartments containing filtering material and the other constituting a precipitating-compartment, a tube extending from the top opening into the precipitating-compartment and a deflecting-plate suspended from said tube.

4. A pair of filters coupled together and each divided into lower filtering-compartments and upper precipitating-compartments and piping connecting one of said precipitating-compartments with the filtering-compartments.

5. A pair of filters, each divided into non-communicating compartments, a pipe connecting a compartment of one filter with a compartment of the other filter, and pipes connecting one of said connected compartments with the remaining compartments.

6. A pair of filters, each divided into non-communicating filtering and precipitating compartments, a pipe connecting the precipitating-compartments and pipes connecting one of the precipitating-compartments to the filtering-compartments.

7. A plurality of filters coupled together by piping and each divided into compartments by a solid unperforated diaphragm and piping connecting each compartment with at least one other compartment.

8. A plurality of filters coupled together by piping and each divided horizontally into compartments by a solid unperforated diaphragm and piping connecting each compartment with at least one other compartment.

9. A filtering-tank having a precipitating-compartment and a lower filtering-compartment and a dished diaphragm dividing said compartments which forms an impurity-col-

lecting bottom for the precipitating-compartments and a solid unperforated top for the filter-chamber.

10. A plurality of filters, each having a precipitating - compartment, pipes connecting said precipitating - compartments, a curved plate secured to the interior of one compartment and forming a water-passage communicating with the connecting-pipe, and a deflecting-plate beneath said water-passage.

11. Two filters coupled together, one having a center tube forming a water-inlet and the other a side inlet passage, and a pipe connecting said filters and serving as an outlet from the first-mentioned filter and as an inlet to said second-mentioned filter and extending into communication with the side passage of said second-mentioned filter.

12. Two coupled-together filters, the first having a center tube forming a water-inlet and the second a side inlet passage, a deflecting-plate beneath said center tube and serving as an outlet for the first filter and an inlet into the second filter; said pipe extending into communication with the side passage of the second filter.

13. Two coupled-together filters each divided into non-communicating precipitating and filtering compartments, one of said filters having an inlet and the other a side passage connecting with the connecting-pipe.

14. A plurality of filters coupled together

and each divided into lower filtering-compartments and upper precipitating-compartments and piping connecting one of said precipitating-compartments with at least one of the filtering-compartments.

35

15. In a water-purifying apparatus, a plurality of tanks, each having non-communicating precipitating and filtering chambers and piping connecting each chamber of said tank with at least one other chamber.

16. In a water-purifying apparatus, a combination of two tanks, each having a precipitating and filtering chamber, two three-way valves, pipes from one of the precipitating-chambers to the three-way valves, pipes from said valves to the filters, and wash-out pipes from said valves, substantially as set forth.

45

17. In a water-purifying apparatus, a combination of two filters, two pipes leading to said filters, each having a three-way valve, and a wash-out pipe from said valves, substantially as set forth.

18. A combination of two filters, a supply- pipe, a horizontal pipe, two pipes leading therefrom, each having a three-way valve, a pipe to each filter from each three-way valve, and a wash-out pipe from said valves.
